UNITED STATES PATENT OFFICE.

JOE B. PROSSER, OF CLINTON, OKLAHOMA.

FEED-SHAFT.

1,243,100.

Specification of Letters Patent. Patented Oct. 16, 1917.

Application filed April 8, 1916. Serial No. 89,916.

To all whom it may concern:

Be it known that I, JOE B. PROSSER, a citizen of the United States, residing at Clinton, in the county of Custer and State of Oklahoma, have invented certain new and useful Improvements in Feed-Shafts, of which the following is a specification.

This invention relates to improvements in shafts for pneumatic drills or other devices, and has for its principal object to provide a feed shaft which is extensible.

Another object of the invention is to provide novel means for retaining the shaft in an adjusted extended position.

15 A further object of the invention is to provide means whereby a desired approximate longitudinal adjustment of the shaft may be obtained, and whereby a minute adjustment may be obtained after the first adjustment.

20 With the foregoing and other objects in view, the invention consists in the novel features of construction, combination and arrangement of parts, as will be more fully described, and illustrated in the accompanying drawings and claimed.

In the drawings,

Figure 1 is a side elevation of the pneumatic drill showing the improved feed shaft operatively associated therewith,

30 Fig. 2 is a longitudinal section through the feed shaft,

Fig. 3 is a side elevation,

Fig. 4 is an elevation, parts being shown in section of the extension member, and,

35 Fig. 5 is a side elevation of the pawl.

Referring to the drawings by numerals, wherein is illustrated the preferred embodiment of my invention, 1 designates a pneumatic drill of any conventional form which, 40 as usual, has extending therefrom the threaded stud 2, upon which is threaded a collar 3 provided with radial handles 4.

The feed shaft comprises a cylindrical tube 5 which is reduced and exteriorly 45 threaded at one end, as at 6 and is open at its opposite end. The reduced end 6 is provided with a threaded bore which communicates with the interior of the tube, and this bore is adapted to receive the 50 threaded shank 7 of a hardened cone shaped bearing point 8. Adjacent the open end of the tube the same is enlarged longitudinally and this enlargement is provided with an opening 9 of any suitable length which is 55 extended laterally at one end and is en-

larged into any suitable shape at its opposite end.

A pawl 10 of a shape to be received within the slot 9 is provided which is mounted for pivotal movement within the slot upon a pin 11 extending through the enlargement. This pawl is provided at the end adjacent the open end of the tube with a depending finger 12 having a beveled under face 13, and at its opposite end is provided with a flat spring 14 for engagement with a portion of the tube to normally hold the finger 12 within the bore of the tube.

A shaft 15 is slidably mounted within the tube 5 and is provided with a series of 70 longitudinally spaced annular shoulders 16, the shaft being tapered from each shoulder to the next succeeding shoulder to form grooves 17 having angular faces. The outer end of this shaft is threaded, as at 18 to 75 receive an interiorly threaded socket 19.

By depressing one end of the pawl 10 the finger 12 may be lifted so as to permit of the shaft 15 being inserted within the tube. Then by releasing the pawl the 80 finger 12 will be caused to engage with the recesses 17 and abut the shoulders 16, the angular face 13 of the finger being adapted for snug engagement with the tapered faces of the grooves. By this arrangement it 85 will be noted that the shaft 15 is secured to slide outwardly relative to the tube 5 upon a pull being exerted thereon, but is prevented from inward movement relatively to the tube by reason of the finger 12 of the 90 pawl engaging the annular shoulders 16.

In use, the device is adapted to be placed with the hardened point 8 engaging against some suitable rigid object and the socket 19 receiving the outer end of the stud 2 of the 95 drill. The shaft 15 may then be moved longitudinally of the tube 5 until the drill is brought into engagement with the object to be operated upon, the pawl 10 being adapted for engagement with one of the 100 grooves to lock the shaft against inward movement from this adjusted position. Now by rotating the collar 3 by means of the handles 4 the same will abut the outer face of the socket 19 and cause the drill 105 to be fed. After the collar has been threaded approximately to the outer end of the stud 2, the same is reversed, and run up upon the stud, and the shaft 15 moved outwardly another notch to cause the end of the 110

stud to lie fully within the socket 19, the feeding operation is then repeated.

In Fig. 4 of the drawings I have illustrated means whereby the feed shaft may be approximately adjusted to a length to extend between the fixed support A and the drill. This means comprises a rod 20 which is provided at one end with a cone bearing point 21 and at its opposite end is threaded, as at 22 to receive an inwardly threaded socket 23, the same being threaded at its outer end for engagement with the exterior threads 6 of the tube 5. By threading the rod 20 upon the tube 5 a rough or approximate adjustment of the device may be obtained and then by making use of the shaft 15 smaller adjustment may be obtained.

From the foregoing description taken in connection with the accompanying drawings it is thought that the construction and operation of the improved shaft will be understood and while I have herein shown and described one specific embodiment of my invention, I do not wish to be limited thereto except for such limitations as the claims may import.

I claim:

1. A device of the character described comprising a tube having a bearing point at one end, and a pivoted pawl near the opposite end projecting into the tube, a shaft longitudinally movable within the tube, a series of annular shoulders on the periphery of said shaft for engagement successively by said pawl as the shaft and tube are moved relatively in a longitudinal direction, said annular shoulders permitting

individual rotation of either shaft or tube, and a socket carried by said shaft.

2. A device of the character described comprising a tube exteriorly threaded at one end, a hardened cone-shaped bearing point detachably carried by said end, a shaft longitudinally adjustable within the tube, a series of angular annular shoulders each having an inclined side formed on the periphery of said shaft, a pawl pivoted on the tube for successive engagement with the shoulders, and permitting free rotation between said shaft and tube, free longitudinal extension therebetween, but locking said parts from contact without disconnecting the pawl, a socket carried by the shaft, and a lengthening rod for the shaft adapted to be engaged with the threaded ends of the tube.

3. The combination with a drill having a threaded stud and a collar threaded on the stud, of an adjustable feed shaft comprising an outer tubular member and a cylindrical member slidably thereinto, interlocking means on the tubular member and the inner member for holding the inner member at different longitudinal positions within the outer member, and a socket on one end of said inner member to receive the threaded stud of the drill and form a bearing for the collar thereon.

In testimony whereof I affix my signature in presence of two witnesses.

JOE B. PROSSER.
